[57] CLAIM

The ornamental design for a handle for a tethered ball, as shown and described.

DESCRIPTION

FIG. 1 is a top front perspective view of a handle for a tethered ball showing my new design;

FIG. 2 is a side elevational view thereof, all sides being identical;

FIG. 3 is a top plan view thereof; and,

FIG. 4 is a bottom plan view thereof.

The broken line showing of a tether portion is to indicate environment only.
